UNITED STATES PATENT OFFICE

HUBER H. ROOT, OF MEDINA, OHIO, ASSIGNOR TO THE A. I. ROOT COMPANY, OF MEDINA, OHIO, A CORPORATION

EDUCATIONAL APPLIANCE AND MAKING THE SAME

Application filed May 12, 1928. Serial No. 277,131.

The object of my invention is to make letters and numerals, that is to say, characters that may be used for the education of children to whom they will appeal as toys. By 5 my invention the letters, type or other characters or shapes may be made at a very low cost especially when, as I prefer, they are made of wood, and yet of light weight, and they may be made of substantial size so that 10 children may readily handle them as playthings and be attractive to children.

My invention consists in whatever is described by or is included within the terms or scope of the appended claims.

15 I shall describe my invention with reference to making letters and numerals of wood, and particularly the letters and other characters, such as "B" "D" "8", etc., that may be termed "closed" characters, and by reason of 20 their form or contour, present especial difficulties.

In the accompanying drawings:

Fig. 1 is a perspective view of several letters made in accordance with my invention;

25 Fig. 2 is a perspective view illustrating the form of blank used in the production of such characters, as the letter "B" for example;

30 Fig. 3 is a perspective view showing the completed blank referred to in the brief description of Fig. 2.

Briefly described, and referring to the production of wooden letters or characters, illustrated, my invention contemplates the formation, as in a wood molding machine, of 35 strips of wood of as great length as may be possible or desirable with grooves or channels where necessary so that the resulting strip or molding has in cross section the contour of part of the letter or character, and then the strip is cut by cross cuts to produce 40 the letters or characters. In the case of those letters which may be referred to as "open" letters or characters, such as letter "H" for 45 example, a simple strip of wood may be used which being grooved at top and bottom by passing through a molding machine will result in a blank having the cross section of the letter with all parts or members of the letter 50 in one piece or integral. In the case of letters

or characters which may be termed "closed", that is to say such letters for example as "B", which preclude an integral or one-piece construction, a molding, 10, may be formed of a single strip such as that shown in Fig. 2 of the drawing which has two parallel grooves or channels, the cross section being the same as that which may be used in producing the numeral "3", and a second flat strip, 11, such as would serve to make the numeral "1" or the letter "I" is provided and the two glued together to produce the built-up blank, 12, shown in Fig. 3 which is then sawed or cut into cross sections to result in the desired letter or character.

The characters, when made of wood, are cut cross grain, which enhances their appearance, and is instructive as to the formation and growth and physical properties of wood.

The character after being formed are 70 smoothed and polished, as by a tumbling machine.

What I claim is:

1. An educational appliance comprising a character such as an alphabetical letter 75 formed of two members joined together side by side, and enclosing a space on all sides, said members being of wood in cross-section showing the cross grain of the wood on the reading surface of the character.

2. The method of producing shapes or forms such as alphabetical letters; having a desired contour which consists in making a plurality of strips which placed side by side have a cross section corresponding to the 85 desired contour certain of such strips being straight in cross section and an associated strip being curved-linear in cross section, the two strips when secured together enclosing a space on all sides, securing such strips together, and then cutting the resulting blank 90 transversely at intervals of its length.

3. The method of producing shapes or forms such as alphabetical letters having a desired contour which consists in longitudinally grooving or channeling a strip of wood and thereby giving it a cross section corresponding to the desired form, attaching a strip straight in cross section to the open side of the groove of the grooved strip, there- 95

by enclosing a space on all sides; and then cutting the composite strips crosswise at intervals along the length thereof.

4. An educational appliance comprising a character such as an alphabetical letter formed of two members joined together side by side, and enclosing a space on all sides, said members being of wood in cross-section showing the cross grain of the wood on the reading surface of the character, the reading surface being polished.

5. The method of producing shapes or forms having a desired contour such as alphabetical characters which consists in longitudinally grooving or channeling a strip of wood and thereby giving it a cross section corresponding to the desired form and then cutting the strip crosswise at intervals along its length and exposing the cross grain as the external, visible surface of the product, and then dressing the surface of the form thus produced.

In testimony whereof I hereunto affix my signature.
